SUPPLYING INK TO INK TRANSFER
MEMBERS

George E. Pelton, Alexandria, Va.

Application September 19, 1932, Serial No. 633,874

34 Claims. (Cl. 197—171)

This invention relates to typing machines, and particularly to means for supplying ink to the writing ribbons or transfer members of such machines while in use, by means of an ink carrying or supply ribbon. The term "ink" is hereinafter used to designate any transfer material for making marks or letters.

In my Patent No. 1,826,568 an ink absorbent supply ribbon, which interwinds with the writing ribbon and thereby transfers ink to said writing ribbon is shown; in my copending application Serial No. 588,932, filed January 26, 1932, a $\frac{1}{6}$ " width substantially non-ink-absorbent ink supply ribbon which interwinds with the writing ribbon, is shown. The present invention relates to improvements in what is shown in said patent and said application and this application is a continuation in part of my said application Serial No. 588,932.

An object of this invention is to provide a writing ribbon which is as much as forty yards in length and which does not interwind with the ink supply ribbon.

Another object is to provide an ink supply ribbon which is not interwound with the writing ribbon, thereby permitting the writing ribbon to occupy all of the space of the typing machine spools, said spools being standard size or being larger than standard size, even large enough to accommodate forty yards of writing ribbon.

Another object is to eliminate the necessity for using two ribbons interwound on the same spool or spools such as used in the above mentioned patent and application; also to make it much simpler and easier and quicker to remove the writing ribbon and to rewind it with its bottom edge placed above in the machine and on the spools so that the unused bottom edge may be used for another long period equal to the first period of use of the first edge. This, of course, is limited to solid color ribbons. It is not customary at present to turn over the solid color ribbons so as to bring the lower edge above and so as to furnish new, unused fabric in the portion or line of the ribbon where the type contact. Since the present invention utilizes the full space of the spool (which is utilized in said patent and said copending application for the writing ribbon and ink supply ribbon which are interwound on the said spool) just for the writing ribbon alone, it is self-evident that there is a vastly longer writing ribbon which means increased writing from the first edge and also from the bottom edge of the ribbon and which totals

a tremendous increase in quantity of work, and all from the same ribbon.

Another object is to simplify the placing of the new ribbon in the machine; also another object is to provide an ink supply ribbon which is put into position at the factory at the time the typing machine or printing mechanism is built and to provide an ink supply ribbon which will last as long as the machine itself and which will not require renewal by a service man at the time he renews the writing ribbon; also to make it a very simple, quick, easy matter to renew the writing ribbon; also to provide method and means whereby the writing ribbon is largely, if not entirely, independent of the ink supply ribbon; also to provide method and means whereby the writing ribbon alone, as it winds up alone on the spool, decides the speed of travel of the spools and thereby also controls the speed at which it travels through the ribbon vibrator as it dispenses ink in its travel from one spool to the other back and forth day in and day out during its entire life.

Another object is to overcome the many difficulties incident to employing two ribbons fastened to and interwound on the same spools, including the difficulties connected with reversing, when the end of the writing ribbon has been reached, without having the type contact several times in the same place on the writing ribbon thereby producing a worn place in the fabric of said writing ribbon before the spool picks up and begins winding said ribbon in the opposite direction.

Another object is to provide an ink supply ribbon in the form of an endless belt which will transfer ink uniformly and evenly and in suitable quantities to exactly replenish the amount of ink dispensed by the writing ribbon; and to secure such even, uniform replenishment of the ink supply of the writing ribbon during operation of the typing machine for fine correspondence in commercial and professional offices, it is absolutely essential to feed the ink from the reservoir by appropriate means to a substantially non-ink-absorptive surface of said supply ribbon.

Another object of this invention is to simplify the feeding of ink to a writing ribbon and to accurately control the rate at which ink is fed to a writing ribbon; also to make it possible to obtain as much writing from multi-color ribbons as from ribbons of one color.

In the accompanying drawings:

Fig. 1 is a plan view of a modified form of

inking means in which an endless auxiliary inking member or belt or supply ribbon is employed to transfer ink to the writing ribbon.

Fig. 2 is an elevation taken approximately on 5 the line 5—5 of Fig. 1.

Fig. 3 is a plan view of another form of inking means using an auxiliary inking belt or supply ribbon for transferring ink to the writing ribbon.

10 Fig. 4 is a plan view of a form of inking means whereby a long ink supply ribbon is employed but which does not interwind on the writing ribbon spools with the writing ribbon but winds up on smaller spools which are turned 15 by the writing ribbon spools.

Fig. 5 is a plan view of another form of inking means using a long ink supply ribbon and supplying ink to an intermediate member which in turn transfers said ink to the writing ribbon.

20 Fig. 6 shows guide channels for guiding the endless ribbon.

This invention may be applied to a typewriter, cash register, adding machine or type mechanism of any kind using a writing ribbon or other 25 ink transfer member.

In the accompanying drawings, for the purpose of illustrating an embodiment of my invention, it is shown as applied to a typewriting machine having a frame 10 and a platen 11, which 30 carries the paper or other material upon which the writing is done. 12 and 13 represent the usual ribbon spools upon which the writing ribbon 14 may be wound and unwound during the use of the typewriter. The ribbon in passing 35 from one spool to the other passes through the usual ribbon guide or vibrator 15, and moves in the vibrator into and out of the writing position in which the writing ribbon's face is struck by or contacted by the type. Any other means 40 for using the ribbon to transfer ink therefrom to a writing surface may be employed.

In accordance with my improved method of supplying ink to a substantially non-absorbent ink supply ribbon of any kind, I provide a stationary wick which may extend into an ink reservoir and which may supply ink to a rotary inking member which is in direct or indirect contact with the thin edge portion of a rotatable member. Said thin edge portion can receive only 50 a very limited amount of ink proportional to the thickness of the edge of said rotatable member. At one portion of the circular path of movement of the said thin edge of said rotatable member, ink is applied to the edge, and at another portion 55 of the path of movement of this edge, the ink is removed from this rotatable member and applied either directly to the face of an endless belt, or endless ink supply ribbon. The ink may also be applied to said thin edge of the 60 rotary member by having this thin edge contact directly with a wick or other capillary member, or it may be applied in some other manner as may be preferable or desirable. To insure a uniform inking of this edge and to prevent 65 the wick from being injured or cut by the thin edge of the rotary member (in case the thin edge contacts directly with a wick or capillary member) it is preferable to have the wick of cylindrical form and rotating at the same peripheral speed as the edge of the rotary member. This insures a uniform deposit of ink on the 70 edge of the rotary member, in that the portion of this member contacting with the wick applies very slight pressure thereto and receives 75 from said wick a small amount of ink which

is deposited on the edge of the rotary member. It may be desirable, however, to use a stationary wick and to have the ink fed to the edge portion of said rotary member from an inking roller which in turn is inked by contact (rolling contact 5 may be desirable) with a wick. The rotary members may receive their rotation directly or indirectly from the movement of the writing ribbon spools or other spools or from an endless belt or ink supply member.

In order to have the largest possible amount of even, uniform writing during the life of the fabric of the writing ribbon, I may use spools for the writing ribbon which are large enough to accommodate a writing ribbon forty yards 10 in length and not over .0035 of an inch in thickness. The present invention, in its various forms, utilizes improved inking means and ink supply belts or ribbons, but it does not use the large 15 machine spools for winding any ink supply members in with the writing ribbon on the same spool and it has the great advantage of the use of an ink supply ribbon without the disadvantages incident thereto such as having to furnish 20 space on the ribbon spools for interwinding the writing ribbon with the ink supply ribbon and also the disadvantages incident to changing ribbons or reversing ribbons or turning the bottom 25 edge up for use in writing.

In the forms of inking means of the present 30 invention, when the typing machine is not in use, as for example at night, the thin edge portion of the disk 30 will, of course, transfer no ink, and consequently ink will only be supplied 35 to the writing ribbon 14 from the ink supply ribbon as ink is dispensed from said ribbon 14 and as it is needed to keep the ink content of the said ribbon 14 uniform and constant.

In Fig. 1 is illustrated an arrangement, whereby ink may be transferred directly to an endless belt or endless ink supply ribbon 20 for transfer to a surface of the writing ribbon 14. In this set-up, I have the inking apparatus and one end of said stationary wick located on top of the central portion of reservoir 22. In Fig. 1 only one rotary member or inking wheel contacts with the end of said stationary wick for supplying a line or lines of ink upon the thin edge portion or periphery of a rotary disk member, and also in Fig. 1 my thin edge transfers ink in the form of a line or lines to a portion of a face of said endless inking belt. Said endless inking belt or ink supply ribbon 20 may be constructed with a series of perforations 42 which may extend along each edge of 50 said endless belt or ink supply ribbon or may extend in one row only equidistant apart for the whole circumference of said belt or ribbon. The spools 12 and 13 may have their top and bottom flanges constructed as gears and the 55 small rollers marked 40 in Fig. 1 may also have their top and bottom flanges constructed as gears meshing with the geared spools 12 and 13. The posts marked 45 with slots 46 show the position of the writing ribbon and the inking belt or supply ribbon when they contact directly for the transfer of ink from the surface of the belt or ribbon 20 to the face of the writing ribbon 14. The teeth of the large spools which wind the ribbon 14 are marked 12a and 13a and 60 the teeth of the small rollers are marked 40a. When we insert a clean, new ink belt or supply ribbon into the machine and a new writing ribbon 14 begins winding on spool 12 as the machine is operated, ink is placed on an outer 65

face of said belt or ribbon 20 and as the writing ribbon winds into spool 12, if said spool 12 winds counter-clockwise, the supply ribbon or belt 20 will move from the inking apparatus over 5 towards spool 12 and as the ribbons contact at post 45 on the left, the writing ribbon 14 will receive ink from said belt or supply ribbon 20 just before said writing ribbon is wound up on the spool 12 and said ribbon 20 will travel from 10 said post 45 across and over to the spool at the right of the machine and around back and again be inked by the inking mechanism located in the central portion of the upper part 15 of the machine directly over the central portion of the ink reservoir and in the centre of the top plate of said machine. It is apparent, therefore, that when winding counter-clockwise, the writing ribbon 14 is inked as it goes away from the impact point of the type with said writing 20 ribbon. If it is desirable in certain types of typing machines, the inking means (pressure roller 34, rotary disk with thin edge, said disk being 30 and said edge 30a, inking roller 26, stationary wick 25, the spring 38 and suitable 25 driving connections or gears) may be located on the side of the ink belt or supply ribbon 20 which is toward the platen and then the spools 12 and 13 may turn in the opposite direction. Or for very bold writing, the inking apparatus 30 may be located as shown in Fig. 1 and the spools 12 and 13 may turn clockwise.

The roller next to spool 12 and the roller next to spool 13 are constructed with projecting pins which fit into the perforations 42. The pins 41 35 are similar to the pins which fit into the perforations of a motion picture machine film and are for the same purpose, viz: to wind the ink supply ribbon or belt step by step through the mechanism always transferring ink therefrom 40 to a face of said writing ribbon 14 during the operation of the machine. The geared spools, the geared rollers and the projecting pins and a portion of said ink supply ribbon or belt carrying ink on its surface, are illustrated in Fig. 2.

45 The construction described has the advantage that a line or lines of ink may be transferred from the ink supply ribbon to a face of a writing ribbon, for a distance on said writing ribbon equal to the length of the space on said ribbon 50 which is marked by the type during the travel of said ribbon from one spool 12 to the other spool 13 back and forth during the operation of said typing machine, as efficiently as when the ink supply ribbon interwinds with said writing 55 ribbon, with very much more space in said spool 12 and spool 13 for writing ribbon since the endless belt form of ink supply ribbon makes it possible to fill the spool 12 or spool 13 with writing ribbon alone, thereby adding 60 very greatly to the amount of writing which can be done by a typing machine without touching the writing ribbon or turning it or renewing it, and also thereby adding greatly to the amount 65 of writing that may be done from a multi-color ribbon in comparison with the amount that can be done when the ribbons interwind. There is the additional advantage that a short ink supply ribbon, which is comparatively inexpensive, may be used for the life of the machine. The end- 70 less belt or ink supply ribbon may be made of very strong, fairly thick material, such as a metallic ribbon, brass, copper, aluminum, steel, iron, or alloys of these or of other metals, or it may be made of any of the materials described 75 in my copending applications Serial No. 588,932,

filed Jan. 26, 1932, and Serial No. 629,078, filed August 16, 1932, or of any other materials preferred. Said belt or ink supply ribbon may have a fabric base impregnated or coated with cellulose ester material, or impregnated or coated with a starch solution or a gum solution and then if desired it may be coated with cellulose ester material; or said belt or ink supply ribbon may be made of absorbent material or partially absorbent material of any suitable kind or character for the required use. I may use a belt or ink supply ribbon which is entirely non-absorbent, or one which has simply an ink-impervious surface on the outer side. The face which receives the line or lines of ink is preferably impervious to ink although not necessarily so. For fine writing of uniform appearance, week in and week out, month after month, it is of course absolutely necessary to feed the ink to a face of a substantially non-ink-absorptive supply ribbon, or to a substantially non-ink-absorptive surface of a supply ribbon. A belt or supply ribbon which is perforated (either one line of perforations or more) and which moves positively step by step as the writing ribbon 20 spools move step by step during the operation of the typing machine, will pick up ink uniformly from the thin edge of said disk 30 and will deliver it in even, uniform quantities to a face of said ribbon 14, and will continue to do this during the life of the fabric of said writing ribbon 14 so as to keep said ribbon uniformly inked. As said ink supply ribbon or belt travels from said inking apparatus to either spool 12 or to spool 13, said ribbon or belt may travel 35 through guide channels shown in Fig. 6 as 18 and 19 which are secured to the inner surface of a portion of said top plate. The means for reversing said writing ribbon spools 12 and 13 are described and shown in great detail in my 40 Patent 1,826,568 above mentioned. When spool 12 reverses and the writing ribbon 14 begins winding on spool 12, the inking belt or ink supply ribbon 20 at once is reversed too and starts travelling in the opposite direction. I prefer to 45 wind the spools 12 and 13 in such direction and to locate the inking apparatus of Fig. 1 in such place that ink may be transferred from the ink supply ribbon and placed on a face of said writing ribbon 14 as it comes away from 50 the vibrator or ribbon guide 15. For certain classes of writing I may employ an edge portion of a rotary disk for feeding ink upon a face of said ink supply ribbon or belt which is .003 to .004 of an inch in thickness, or for writing with pica type where I desire a great deal of ink in each impression and desire plenty of ink to soak into the fibres of the writing paper itself so that erasures may be difficult to make, and so checks may be difficult to raise, I may 55 employ an edge portion which is .006 to .007 of an inch in thickness and for writing with very large type or type such as is commonly called "bulletin" type, I may employ an edge portion that is even thicker. If the edge portion is recessed or serrated, then the edge portion may be thicker still. I do not limit myself in any way as to the thickness of said edge portion but it is usually preferable to have same of less thickness than the height of the type used in the typing mechanism. The edge may be recessed so as to make a line or lines of fine dots extremely close to each other, or short lines which look like short dashes, equidistant apart 70 75

may be made, or any other type of line or lines desired for the work in hand.

It has been my experience in using typing machines of the kind wherein the writing ribbon 5 and ink supply ribbon interwind that unless an ink supply ribbon which is extremely thin is used, the supply ribbon takes so much space on the spool that it is impossible to use a very long writing ribbon; also the ink supply ribbon has 10 to be slightly longer than the writing ribbon at all times or the ribbons do not reverse promptly when an end is reached. By using an endless belt such as herein described, these and other difficulties are obviated. No matter if the belt 15 or ink supply ribbon is quite thick, it takes up no space on the spool 12 or the spool 13 and there is an incentive to employ a very large spool for winding the writing ribbon now that the ink supply ribbon no longer has to be wound 20 up with said writing ribbon, especially since the only limitation upon the amount of even, uniform writing possible with this type of machine is the length of the writing ribbon and the durability of the fabric of said writing 25 ribbon. When the ink supply ribbon is interwound with the writing ribbon, it is also extremely difficult to always keep the writing ribbon taut as during the use of the writing ribbon and the ink supply ribbon, their relative length 30 may change. Especially is this the case if an inferior ink supply ribbon is used. Another difficulty which arises when the ribbons interwind on the same spool is due to the fact that when the ribbons are new they wind much tighter than 35 when the writing ribbon has been used for a great deal of writing. As it becomes worn and its surface mussed and worn, the fabric of the writing ribbon becomes baggy and wavy and it does not wind tightly on the spool and the ink 40 supply ribbon accordingly cannot wind up tightly and often this results in reversing troubles due to the writing ribbon not having the same relative length with respect to the ink supply ribbon which is required for prompt reversing of the 45 spools when an end of the writing ribbon is reached. By using the endless belt and not interwinding with the writing ribbon, all of these difficulties are swept aside at once. It is now a 50 very easy, simple matter to lift a spool of writing ribbon out of the machine but when the ribbons are interwound, it is slow and difficult and one has to be extremely careful not to injure the very thin, ink supply ribbon and not to get it twisted or broken. It is difficult to permanent- 55 ly fasten a thin ink supply ribbon to the hub of the spool 12 or 13 so that it is certain to remain fastened securely during the life of the fabric of the writing ribbon. However, if one uses an endless belt for an ink supply ribbon, 60 it removes this additional difficulty automatically as said endless belt never has to be fastened to any spool of any kind at an end or otherwise. It is of inestimable value to get rid of all of these difficulties and at the same time 65 have the spool 12 or 13 free for writing ribbon. This endless belt may be $\frac{1}{8}$ of an inch wide or as wide as the writing ribbon or it may be as wide as standard motion picture film and may be made of such material, or of kodaloid or celluloid or cellulose acetate or inflammable film, 70 with one or more series of perforated holes for drawing it around step by step uniformly and so as to feed an even and uniform amount of ink to its surface and in turn to the surface of 75 said writing ribbon. Any other suitable means

for moving said endless belt or ink supply ribbon may be used.

In the construction shown in Fig. 3, I use the endless belt or ink supply ribbon but I do not actually contact said writing ribbon's surface with a surface of the endless belt or ink supply ribbon in order to effect a transfer of ink from the latter to the writing ribbon. Instead I place a rotary member between said writing ribbon's surface and the surface of said ink supply ribbon. I dispense with the use of the posts 45 and the slots 46 of Fig. 4. The rotary member above mentioned may be a thin edged disk or any type of rotary member which will uniformly and evenly transfer the ink, which is fed to it by the ink belt or ink supply ribbon, to the proper portions of a face of said writing ribbon. While in said drawing (Fig. 3) certain rotary members are shown, including two pressure rollers 52 and 54 and the rotary disk 53, 20 I do not limit myself to this particular type of mechanism for feeding ink from a surface of said ink supply ribbon to a surface of the writing ribbon. The same inking apparatus and the same ink supply ribbon or inking belt (endless) 25 may be used for the set-up shown in Fig. 3 as is used where the ink supply ribbon and the writing ribbon contact in the slot 46 shown in Fig. 1.

In Fig. 4 is illustrated an arrangement whereby I employ a very thin ink supply ribbon which travels faster than the writing ribbon and which is of sufficient length that in spite of its faster rate of travel it does not come to an end until the correct time which is the time when the writing ribbon comes to an end. The two ribbons are of such length that they may always reverse at the same time and may travel in the same direction, and yet said ribbons do not interwind with each other. An end of said ink supply ribbon is fastened permanently to the hub 30 of roller 60 near spool 12 and the other end is fastened to the hub of roller 60 near spool 13. The inking means for applying a line or lines of ink to said ink supply ribbon is similar to that shown in Figs. 4 and 6 above. This construction is an improvement over the construction whereby the ink supply ribbon interwinds 35 with the writing ribbon.

In Fig. 5 the ribbons do not actually contact but as is the case in Fig. 3, there is an intermediate rotary member between the ribbons which is of similar construction to that shown in Fig. 3. By the use of inking means and apparatus, such as described, it is no longer necessary to select a cheap cotton ribbon which is full of ink in order to be economical. One may now employ a very fine writing ribbon which of itself is incapable of carrying much ink but by means of the inking apparatus described herein, this strong, durable writing ribbon may be utilized for a very long period and ink transferred from a supply ribbon and distributed upon its face uniformly as it travels from spool to spool, causes the ink content at all times to remain just about the same as when it was new and unused and had just been inked at the ink ribbon factory. If a solid color ribbon be used for the writing ribbon, it is only reasonable after the upper edge portion of said ribbon becomes worn to place the lower edge above and rewind 55 said ribbon to this end and then use said sixty yard ribbon again just as one would use a new ribbon. This means a typing machine of entirely new capacity for fine writing. Where the typing machine used is one where the type con- 60

tact with the said writing ribbon's surface by pressure instead of by cutting impact and blows, it is possible to utilize said 40 yard ribbon for a period of as much as five years without changing said ribbon except to reverse its edges.

The present invention, even more than that of Patent 1,826,568, makes a long fibre silk writing ribbon of even greater worth to the typist or operator of a typing machine or mechanism of any kind which employs an inked ribbon in making impressions on a surface. Just as I can add to the durability of the writing ribbon and add to its length have I directly increased the efficiency of the present invention. But the present invention has the advantages of an ink supply ribbon for feeding ink to the writing ribbon without the disadvantage of the above patent and application that said ink supply ribbon has to interwind with the writing ribbon, thereby taking up a large and very valuable space in the spool 12 or 13. The only limit as to quantity of writing of substantially uniform, rich color and fine appearance is that set by the durability of the fabric which composes said ribbon.

25 As fully described and illustrated in the pending application No. 588,932 filed January 26, 1932, the line or lines of ink can be readily transferred to that portion (upper, lower, or any intermediate portion) of the writing ribbon's surface 30 which it is desired should receive the ink, by simply raising or lowering the inking mechanism. In the case, for example, of a black and red ribbon used in combination with an ink reservoir and with an ink supply ribbon that is of materially less width than the writing ribbon, the ink reservoir is raised to the proper height to feed the narrow ink supply ribbon well above the upper portion of the red ink portion of the writing ribbon.

40 It is readily apparent that the present invention provides a typewriter capable of a vastly increased amount of neat writing. The present invention also simplifies the manner of replacing a writing ribbon because the writing ribbon alone 45 is wound on spools 12 and 13 and readily may be removed from the machine.

It will, of course, be understood that the devices and apparatus and equipment described herein may be used on any typing or printing mechanism 50 or mechanisms employing type and a transfer member, whether said member is in the form of a ribbon, sheet, band, or any other form.

While the ink employed may be a liquid, yet it is to be understood that any other transfer material 55 which may be placed upon the edge of a disk or rotary member as needed, and in turn placed upon the surface of the ink supply ribbon for transfer to the writing ribbon, may be employed.

In my United States Patent No. 1,826,568 (issued October 6, 1931) I disclosed the idea of feeding ink from an ink pad by capillary action across the entire absorbent face of a supply ribbon which interwinds with a writing ribbon and again by capillary action feeds ink from its entire face to the writing ribbon. In the present application I have hereinabove disclosed the idea of a much more restricted feed of ink in the form of a line of liquid ink which is fed to a substantially non-ink-absorptive surface of a supply ribbon. This 70 ink may be fed in a solid line or a line made up of a series of dots or dashes. The all important thing is that the ink be not absorbed by the ink supply ribbon but that it shall be on the surface for the very slight length of time until it contacts with the writing ribbon which almost in-

stantly absorbs it, leaving the surface of said supply ribbon substantially free of ink and ready to receive a new supply of ink for transfer to the writing ribbon. The supply ribbon, not being able to absorb the ink, must transfer ink with a high degree of accuracy and precision, giving up to said writing ribbon the correct amount of ink to replenish the ink expelled in writing. This process may be repeated indefinitely until the writing ribbon's fabric itself is considerably worn, thus insuring even appearance for the writing and making of the writing ribbon an important writing instrument which no longer is required to carry more than a very slight reserve ink supply.

I claim as my invention:

1. In a typing machine, the combination of a writing ribbon, an ink-supply ribbon in the form of an endless belt or band, which receives ink from an ink reservoir or other ink supply in said machine, to supply said ink to said writing ribbon, and means for moving the writing ribbon and the ink-supply ribbon.

2. In a typing machine, the combination of a writing ribbon, and spools on which the same is wound, means for moving said ribbon between the type and the surface to be typed, an ink-supply ribbon, said writing ribbon being wound on said spools independently of said ink supply ribbon, and an ink supply in a stationary wick for transfer to said ink-supply ribbon and to said writing ribbon.

3. In a typing machine, the combination of a writing ribbon, an ink supply ribbon, spools on which only said writing ribbon is wound and which contacts with said supply ribbon, driving connections between the writing ribbon and the ink supply ribbon spools, a reservoir containing ink and containing at least a portion of an inked wick, and means for feeding ink from said inked wick to said supply ribbon and means for transferring ink to said writing ribbon.

4. In a typing machine, the combination of a writing ribbon and an ink supply ribbon, two sets of spools for winding a writing ribbon and an ink supply ribbon, driving connections between a writing ribbon spool and an ink supply ribbon spool, an ink reservoir, and inking means for placing ink from said reservoir upon a surface of said ink supply ribbon for transfer later to a surface of said writing ribbon.

5. In a typing machine, the combination of a writing ribbon, a reservoir of ink, a wick or capillary member, an ink supply ribbon and means for applying ink to a face of said ink supply ribbon for transfer to a surface of an intermediate member which in turn transfers said ink to a face of said writing ribbon.

6. In a typing machine, the combination of a writing ribbon spool on which said writing ribbon alone is wound, a reservoir of ink, a wick or capillary member, an ink supply ribbon and means for applying ink to a face of said ink supply ribbon for transfer to a surface of an intermediate member which in turn transfers said ink to a face of said writing ribbon.

7. In a typing machine, the combination of a reservoir containing a wick and an ink supply, a writing ribbon, at least one inking apparatus and at least one end of said wick connected with said inking apparatus, and an ink supply ribbon in the form of an endless band which receives ink from said wick; said writing ribbon winding on its own spools and said ink supply ribbon winding around smaller spools or rollers which

are turned by gear connections or other driving means.

8. In a typing machine, the combination of an ink supply, a writing ribbon which winds up on its own spools and an ink-supply ribbon which winds up on other spools which are turned by the writing ribbon spools.

9. In a typing machine, the combination of an ink reservoir adapted to carry ink, a writing ribbon which winds up on its own spools, and an ink supply ribbon which winds up on its own spools, geared spools and geared wheels or rollers or rotary members for winding said writing ribbon and said ink-supply ribbon; at least one gear 15 of said spool meshing with at least one gear of said rotary member or roller or wheel.

10. In a typing mechanism, the combination of a writing ribbon and an ink supply ribbon, said ribbons travelling in separate paths and having 20 only short lengths of both ribbons in contact at a time, and means for placing ink on said supply ribbon for transfer to said writing ribbon.

11. In a typing mechanism, the combination of a writing ribbon, spools on which said writing 25 ribbon only is wound, an ink supply ribbon contacting only with portions of said writing ribbon which are exposed while being wound from one spool to another, and means for supplying ink to said supply ribbon for transfer to said writing 30 ribbon.

12. In a typing mechanism, the combination of a writing ribbon and an ink supply ribbon, means for guiding said ribbons in separate paths which meet only along a short length of said writing 35 ribbon, and means for applying ink to said supply ribbon for transfer to said writing ribbon at the meeting of said ribbons.

13. In a typing mechanism, the combination of a writing ribbon, spools on which said writing 40 ribbon only is wound, an ink supply ribbon in the form of an endless band, means for guiding said ribbons into contact, and means for supplying ink to said supply ribbon for transfer to said writing ribbon.

45 14. In a typing mechanism, the combination of a writing ribbon, spools on which said writing ribbon only is wound, means associated with said typing mechanism for turning said spools to advance said ribbon, an ink supply ribbon having a short part only thereof in contact with a part 50 of said writing ribbon which is exposed while being wound from one spool to another, means for supplying ink to said supply ribbon for transfer to said writing ribbon, and means for imparting motion to said supply ribbon from a spool.

55 15. In a typing mechanism, the combination of a writing ribbon and an ink supply ribbon, separate means for imparting motion to each of said ribbons for moving the same in separate paths 60 which meet at one or more points to bring said ribbons into contact, and means for supplying ink to said supply ribbon for transfer to said writing ribbon at the contact between said ribbons.

65 16. In a typing mechanism, the combination of a writing ribbon of low ink-carrying capacity and a substantially non-absorbent supply ribbon, said ribbons travelling in separate paths and having only short lengths of both ribbons in contact at 70 a time, and means for placing ink on said supply ribbon for transfer to said writing ribbon and including a reservoir for liquid ink.

75 17. In a typing mechanism, the combination of a thin silk writing ribbon of relatively low ink- carrying capacity and an ink supply ribbon, said

ribbons being guided in separate paths and having only short lengths of said ribbons in contact at a time, an ink supply reservoir for liquid ink, and means for placing ink from said reservoir on said supply ribbon for transfer to said writing ribbon.

80 18. In a typing mechanism, the combination of a writing ribbon made mainly of long fibered silk, an ink supply ribbon of substantially non-absorptive material, spools on which said writing ribbon is wound, means for guiding said ink supply ribbon into contact with such portions only of said writing ribbon which are exposed while being wound from one spool to another, and means for supplying ink to said supply ribbon.

85 19. In a typewriting machine, the combination of a writing ribbon, spools upon which said writing ribbon only is wound, an ink supply ribbon contacting only with portions of said writing ribbon which are exposed while being wound from one spool to another, means for supplying ink to said supply ribbon for transfer to said writing ribbon, and an ink supply reservoir from which ink is supplied to said supply ribbon, and a wick 90 for conducting ink from said reservoir.

95 20. In a typing mechanism, the combination of a writing ribbon and an ink supply ribbon, said ribbons travelling in separate paths and having only short lengths of ribbons in contact at a time, a reservoir for liquid ink, a disk revolving in contact with said supply ribbon and receiving ink from said reservoir, and means actuated by the movement of said writing ribbon for imparting movement to said supply ribbon.

100 21. In a typing mechanism, the combination of a writing ribbon and an ink supply ribbon, said ribbons travelling in separate paths and having only short lengths of ribbons in contact at a time, means actuated by said typing mechanism for advancing said writing ribbon to place different 40 portions thereof into printing position, means for actuating said ink supply ribbon from the movement of said writing ribbon, means for placing ink on said supply ribbon for transfer to said writing ribbon, and means for driving said ink 45 placing means from said supply ribbon.

105 22. In a typing mechanism, the combination of a writing ribbon, spools on which said writing ribbon only is wound, an ink supply ribbon in the form of an endless band, means for guiding said ribbons into contact, and a stationary wick from which ink is supplied to said supply ribbon for transfer to said writing ribbon.

110 23. In a typing mechanism, the combination of a writing ribbon and an ink supply ribbon, a set 55 of spools for each ribbon, means for guiding said ribbons into contact to transfer ink from said supply ribbon to said writing ribbon, an ink reservoir, and a stationary wick extending into said reservoir and from which ink is supplied to said supply ribbon.

115 24. In a typing mechanism, the combination of a writing ribbon and an ink supply ribbon, a set 60 of spools for each ribbon, means for guiding said ribbons into contact to transfer ink from said supply ribbon to said writing ribbon, means for supplying ink to said supply ribbon, and a gear driving connection between said sets of spools.

120 25. In a typing mechanism, the combination of a writing ribbon, spools on which said writing ribbon only is wound, an ink supply ribbon in the form of an endless band, means for guiding said ribbons into contact, means for supplying ink to said supply ribbon, a gear actuated by a ribbon 70 spool, and a gear meshing with said first men- 75

- tioned gear to impart movement to said supply ribbon.
26. In a printing machine, the combination of a printing ribbon impregnated with ink, a non-absorptive ribbon adapted to receive and transfer ink to said printing ribbon, means for causing an inked side of the non-absorptive ribbon to contact progressively with the printing ribbon, printing means coactive with the printing ribbon 10 to form inked impressions, guiding means for the non-absorptive ribbon withholding the same from the field of printing action of the printing means, a pulley supported on a fixed axis and engaged and driven by said non-absorptive ribbon, an ink 15 applying disk supported to rotate about an axis parallel to the pulley axis and yieldingly urged toward said pulley to contact one face of said non-absorptive ribbon at a point where the opposite face is in contact with said pulley, an ink 20 reservoir below the level of said disk, a roller supported to rotate about an axis parallel to that of said pulley and disk and contacted at its periphery by said disk, said pulley, disk and roller being rotatively driven by said non-absorptive ribbon, and a wick means extending into said reservoir from the periphery of said roller for conveying 25 ink from the reservoir and applying a film of ink to the periphery of the roller.
27. In a typewriter, the combination of a writing ribbon carrying a small reserve supply of ink, an ink reservoir, a non-absorptive endless ink carrier ribbon having a surface adapted to contact with said writing ribbon, and means for placing ink from said reservoir upon said surface of said 30 ink carrier ribbon for transfer to a face of said writing ribbon.
28. In a typing machine, the combination of a writing ribbon, an ink reservoir, a substantially non-absorptive endless ink carrier ribbon, means 35 for placing ink from said reservoir upon a surface of said ink carrier ribbon in the form of at least one line, and means for transferring said ink from said carrier ribbon to the upper, lower or any intermediate portion of a face of said writing 40 ribbon.
29. In a typing machine, the combination of a writing ribbon, an ink reservoir, a non-absorptive endless ink carrier ribbon having a surface adapted to contact with the writing ribbon and means 45 having a rolling contact with said supply ribbon and receiving ink from said reservoir and depositing it on said carrier ribbon.
30. In a typing machine, the combination of a writing ribbon, an ink reservoir, a substantially non-ink-absorptive supply ribbon of cellulose acetate and means for placing ink from said reservoir upon a face of said supply ribbon for transfer to said writing ribbon during operation of said machine.
31. In a typing mechanism, the combination of a writing ribbon, an ink reservoir, a substantially non-ink-absorptive supply ribbon consisting at least in part of cellulose acetate and having a surface adapted to contact with said writing ribbon, and means for placing ink from said reservoir upon said surface of said ink supply ribbon for transfer to a face of said writing ribbon.
32. In a typing mechanism, the combination of an inked writing ribbon, an ink reservoir, a substantially non-ink-absorptive endless ink supply ribbon which is thinner than the said writing ribbon and having a face adapted to contact with said writing ribbon, and means for placing ink from said reservoir upon said face of said supply ribbon for transfer to a face of said writing ribbon; said ink supply ribbon being unlinked when first put in service.
33. In a typing machine, the combination of a writing ribbon carrying the optimum quantity of ink for the character of impression desired, a substantially non-absorptive endless ink supply ribbon having at least one smooth, even surface, 20 the two ribbons contacting with each other, an ink reservoir, and means for placing ink from said reservoir upon said ink supply ribbon in the right quantity to maintain the ink content of the writing ribbon substantially uniform and the same, 25 and means for moving said ribbons so as to transfer said ink from said ink supply ribbon to said writing ribbon continuously during use of said writing ribbon, in uniformly even quantities, said ink being transferred in the form of at least one 30 line, from the ink reservoir to the smooth surface of said supply ribbon.
34. In a printing machine, the combination of a printing ribbon impregnated with ink, a non-absorptive endless ribbon adapted to receive and transfer ink to said printing ribbon, means for causing an inked side of the non-absorptive endless ribbon to contact progressively with the printing ribbon, printing means coactive with the printing ribbon to form inked impressions, guiding means for the non-absorptive endless ribbon withholding the same from the field of printing action of the printing means, a pulley engaged and driven by said non-printing ribbon, an ink supply disk supported to rotate about an axis 40 parallel to the pulley axis, yielding means for effecting relative movement of said pulley and disk to urge one toward the other to cause said disk to contact one face of said non-absorptive endless ribbon at a point where the opposite face 45 is in contact with said pulley, an ink reservoir below the level of said disk, a roller supported to rotate about an axis parallel to that of said pulley and disk and contacted at its periphery by said disk; said pulley, disk, and roller being rotatively 50 driven by said non-absorptive endless ribbon, and a wick means extending into said reservoir from the periphery of said roller for conveying ink from the reservoir and applying a film of ink to the periphery of the roller.

GEORGE E. PELTON.
